7 Claims. (Cl. 250—27)

My invention relates to electrical apparatus and particularly to electronic circuits of the multivibrator type.

Many electronic systems require a source of sharp pulses of short time duration, and having an essentially square wave form. A number of multivibrator circuits which exist in the prior art of which I am aware, attempt to produce such pulses. These circuits, however, leave much to be desired in the wave form and amplitude of the output pulse.

It is, accordingly, a broad object of my invention to provide an improved multivibrator circuit.

It is another object of my invention to provide a multivibrator circuit which will produce voltage pulses of short time duration having steep rise and decay characteristics, and having an amplitude substantially equal to that of the supply voltage.

In accordance with my invention, I provide a multivibrator circuit comprising a pair of electronic tubes, one of which may be a triode and the other a pentode. The circuit of my invention is arranged so as to provide feedback from the triode, to the cathode, and the screen and suppressor grids of the pentode, whereby voltage pulses having desirable characteristics including very short rise and decay times and relatively large amplitude are provided.

Other objects and advantages of my invention will appear from the following description of a preferred embodiment, taken in connection with the accompanying drawing, in which the single figure is a schematic diagram of a preferred embodiment of my invention.

The multivibrator circuit shown in the drawing includes a pair of electronic tubes, one of which may be a triode 11 and the other a pentode 13. The cathodes 15, 17 of these tubes are connected through a common bias resistor 19 to ground 21. The positive terminal 23 of a direct current anode potential source (not shown) is connected through a first resistor 25 to the anode 27 of the pentode 13, and through second and third resistors 29, 31 to the anode 33 of the triode 11. The anode 27 of the pentode 13 is connected through a capacitor 35 to the control grid 37 of the triode 11. A fourth resistor 39 is connected between the control grid 37 and cathode 15 of the triode 11. The screen grid 41 of the pentode 13 is connected to the anode 33 of the triode 11. The control and suppressor grids 43, 45 of the pentode 13 are connected to ground 21. A by-pass capacitor 47 is connected from the junction of the second and third resistors 29, 31

2

to ground 21. Terminals 49 are provided for application of trigger pulses between the control grid 37 of the triode 11 and ground 21. Output pulses are taken from terminals 51 provided between the anode 27 of the pentode 13 and ground 21.

In the operation of the circuit, the triode 11 is normally conductive and the pentode 13 is normally non-conductive. To get an output pulse, a negative trigger pulse is applied to the grid 37 of the triode 11. This reduces the plate current of the triode 11, which in turn decreases the voltage drop across the cathode bias resistor 19. Reduction in voltage drop across the cathode bias resistor 19 makes the pentode control and suppressor grids 43, 45 more positive with respect to the cathode 17. At the same time the plate voltage on the triode 11 has increased which has the effect of making the pentode screen grid 41 more positive with respect to the cathode 17. As a result of these effects which operate simultaneously, the pentode 13 becomes suddenly conductive. The anode voltage of the pentode 13 is lowered, making the control grid 37 of the triode 11 more negative. This action is cumulative until the triode 11 is cut off and the pentode 13 is fully conductive. The coupling capacitor 35 then begins to charge through the fourth resistor 39 making the control grid 37 of the triode 11 more positive. This action continues until the cut-off point is reached, at which time the triode 11 again conducts. Current through the triode will then increase the voltage drop across the cathode bias resistor 19 which will tend to make the pentode control and suppressor grids 43, 45 more negative. At the same time, the plate voltage on the triode 11 has decreased, which has the effect of making the pentode screen grid 41 more negative with respect to the cathode 17. These effects are cumulative until the pentode 13 is cut off and the triode 11 is again fully conductive.

In the practice of my invention I have used the following circuit constants with good results: pentode tube 13, type 6AG7; triode tube 11, type 12AU7 (sections connected in parallel); first resistor 25, 22,000 ohms; second resistor 29, 6,200 ohms; third resistor 31, 2,800 ohms; fourth resistor 39, 100,000 ohms; cathode bias resistor 19, 500 ohms; coupling capacitor 35, 4 to 30 micro-microfarads; by-pass capacitor 47, 0.5 micro-farad.

I am aware that some modifications of the circuit shown and described could be made without departing from the scope of my invention. I desire, therefore, to be limited only insofar

as is necessitated by the prior art and the spirit of the appended claims.

I claim as my invention:

1. A multivibrator circuit comprising a first electronic tube having an anode, a cathode, and a control grid, a second electronic tube having an anode, a cathode, a control grid, a screen grid, and a suppressor grid, a bias resistor connected between said cathodes and ground, means connected to supply anode potential to said tubes, means coupling the anode of said second tube to the control grid of said first tube, a connection from the anode of said first tube to the screen grid of said second tube, and connections from the suppressor and control grid of said second tube to ground.

2. A multivibrator circuit comprising a first electronic tube having an anode, a cathode, and a control grid, a second electronic tube having an anode, a cathode, a control grid, a screen grid, and a suppressor grid, a bias resistor connected between said cathodes and ground, means connected to supply anode potential to said tubes, means coupling the anode of said second tube to the control grid of said first tube, a connection from the anode of said first tube to the screen grid of said second tube, connections from the suppressor and control grid of said second tube to ground, and means to apply a trigger pulse to the control electrode of said first tube.

3. A multivibrator circuit comprising a first normally conductive electronic tube having an anode, a cathode, and a control electrode, a second normally non-conductive electronic tube having an anode, a cathode, control, screen, and suppressor grids, means connected to supply direct current anode potential to said tubes, conductors connecting said cathodes together and through a bias resistor to ground, means coupling the anode of said second tube to the control grid of said first tube, means connecting the anode of said first tube to the screen grid of said second tube, conductors connecting the control grid and suppressor grid of said second tube to ground, and means for applying a negative trigger pulse to the control grid of said first tube.

4. A multivibrator circuit comprising a first normally conductive electronic tube having an anode, a cathode, and a control electrode, a second normally non-conductive electronic tube having an anode, a cathode, control, screen, and suppressor grids, means connected to supply direct current anode potential to said tubes, conductors connecting said cathodes together and through a bias resistor to ground, means including a capacitor for coupling the anode of said

second tube to the control grid of said first tube, means connecting the anode of said first tube to the screen grid of said second tube, conductors connecting the control grid and suppressor grid of said second tube to ground, and means for applying a negative trigger pulse to the control grid of said first tube.

5. A multivibrator circuit comprising a first normally conductive electronic tube having an anode, a cathode, and a control electrode, a second normally non-conductive electronic tube having an anode, a cathode, control, screen, and suppressor grids, means connected to supply direct current anode potential to said tubes, conductors connecting said cathodes together and through a bias resistor to ground, a capacitor connected between the anode of said second tube and the control grid of said first tube, and a resistor connected between the control grid and cathode of said first tube, means connecting the anode of said first tube to the screen grid of said second tube, conductors connecting the control grid and suppressor grid of said second tube to ground, and means for applying a negative trigger pulse to the control grid of said first tube.

6. A multivibrator circuit comprising a first electronic tube having an anode, a cathode, and a control grid, a second electronic tube having an anode, a cathode, control, screen, and suppressor grids, a common cathode bias resistor, and coupling means connected to provide feedback voltage from said first tube to the control, screen, and suppressor grids of said second tube.

7. A multivibrator circuit comprising a first electronic tube having an anode, a cathode, and a control grid, a second electronic tube having an anode, a cathode, a control grid, a screen grid, and a suppressor grid, a bias resistor, means for connecting said cathodes through said bias resistor to a point of reference potential, means coupling the anode of said second tube to the control grid of said first tube, means coupling the anode of said first tube to the screen grid of said second tube, and means coupling the control and suppressor grids of said second tube and the control grid of said first tube to said point of reference potential.
